WASHING MACHINE

Dennis B. D. Blake, Danville, Ill.

Application September 5, 1939, Serial No. 293,376

1 Claim. (Cl. 68—54)

My invention relates to a washing machine which is characterized by an improved agitating arrangement and driving mechanism therefor, and which washes and dries in the same container.

In present type washing machines, wringing of the clothes is customarily accomplished either by manually feeding the separate washed pieces through a roll wringer, or manually transferring the washed pieces to a separate spinner type of wringer, or by spin drying the pieces in the same container in which they are washed. The first two types require an objectionable handling of the separate pieces, while in the last-noted type, it is necessary to draw or even waste the suds or other cleansing liquid from the machine.

It is, therefore, one object of my invention to provide a washing machine in which a succession of batches of pieces may be washed and spun damp dry in the same container without necessitating the withdrawal or loss of the suds.

A further object is to devise a washing machine in which the detergent action is effected by agitating devices which periodically reverse the movement of the pieces being washed and directs masses of suds along opposite sides of and through the pieces.

A further object is to provide a machine of the character indicated having cooperating agitating devices which creates a suds turbulence that tumbles and shifts the pieces to and fro in the suds and substantially free of contact with the enclosing basket.

A further object is to devise a washing machine of the vertical axis type in which the movements of oppositely acting groups of agitating blades are arranged to compensate for the difference in their radial distances from the axis of the machine, thus insuring that the respective blades will move with equal speed.

These and further objects of my invention will be set forth in the following specification, reference being had to the accompanying drawings, and the novel means by which said objects are effectuated will be definitely pointed out in the claim.

In the drawings:

Figure 1 is a sectional elevation of my improved washing machine showing in washing position the basket for receiving the pieces to be washed.

Fig. 2 is a view similar to Fig. 1, but showing the basket in elevated or spinning position for centrifugally extracting the cleansing liquid from the pieces.

Fig. 3 is a fragmentary and enlarged sectional elevation of the central portion of the basket and the inner agitating blades.

Fig. 4 is a section along the line 4—4 in Fig. 1, looking in the direction of the arrows, and show-

ing the relation of the inner and outer agitating blades.

Figs. 5 and 6 are sections along the lines 5—5 and 6—6, respectively, in Fig. 1, looking in the direction of the arrows, and showing a portion of the driving mechanism for the two sets of agitating blades.

Fig. 7 is an enlarged section along the line 7—7 in Fig. 1, looking in the direction of the arrows, and showing a portion of the agitating blades driving mechanism.

Fig. 8 is an enlarged section along the line 8—8 in Fig. 6, looking in the direction of the arrows.

Fig. 9 is an enlarged, sectional elevation of the lower portion of the machine, as viewed in Fig. 1, showing the clutch which transmits the drive to the washing devices of the machine and also the mechanism for thereafter elevating the basket to spinning position.

Fig. 10 is a fragmentary, sectional view showing the clutch illustrated in Fig. 9 in disengaged position.

Referring to Fig. 1 of the drawings, the numeral 10 designates a casing that may be supported by the usual casters 11 and which has secured to the interior thereof at a convenient distance above the floor a plurality of brackets 12 that are spaced around the casing. These brackets support a tub 13 that opens upwardly and which may be closed by the usual cover 14.

The casing 10 is indicated as possessing a circular shape, but may have other configurations and, at a convenient distance from the bottom thereof, the casing wall is strengthened by a lower, channel-shaped strut 15 that is also utilized as a support for a portion of the driving mechanism of the machine, as hereinafter described. To this end, a main drive motor 16 is carried by a bracket 17 that is in turn bolted to the strut 15 and to the shaft of the motor is secured a pulley 18 having dual grooves (see Fig. 6).

A belt 19 operates in one of these grooves and also around a pulley 20 that is fast on the shaft of a worm 21 (see Fig. 1) that is journaled in a housing 22 secured to the underside of the strut 15. The worm 21 meshes with a worm gear 23 that is secured to a shaft 24 and this shaft extends upwardly through the strut 15 and is fixed to a crank arm 25 that rotates in a horizontal plane.

The free end of the crank 25 is pivotally connected to an L-shaped yoke 26 having a pair of arms 27 and 28 (Fig. 6). The arm 27 is pivotally connected to one end of a link 29 that extends across the machine just above the strut 15 and has its opposite end pivotally attached to a rock arm 30 that is fast on a sleeve 31 that is axially aligned with the tub 13.

Referring to Fig. 9, the upper end of the sleeve 31 has secured thereto a flange 32 having a

plurality of circumferentially spaced apertures 33 for receiving driving pins 34 that are fixedly mounted in a cooperating flange 35 that is secured to the lower end of a sleeve 36. The flanges 32 and 35, together with the pins 34, constitute a clutch for establishing and interrupting the drive to certain agitating devices hereinafter described. The axis of the sleeve 36 is in alignment with the axis of the sleeve 31 and the former sleeve extends upwardly 10 through the bottom of the tub 13 in coaxial relation thereto and is journaled in a concentric sleeve 37 whose lower end is mounted in the bottom of the tub. At its upper end the sleeve 36 is keyed to the upper end of the concentric sleeve 38 that extends downwardly and surrounds the sleeve 37, but is spaced therefrom, and at its lower end is provided with an annular flange 39 that is secured to the bottom of a cylindrical basket 40 whose bottom and peripheral wall may be perforated in the usual manner. Only a few 20 of these perforations are illustrated. The peripheral wall of the basket (see Figs. 1 and 4) is provided with a plurality of equispaced, radially disposed blades 41 which constitute an outer group of agitating devices.

Referring to Figs. 6 and 7, the other yoke arm 28 is pivotally connected to one end of a link 42 whose opposite end is pivotally secured to the free end of a rock arm 43 that is keyed to a short sleeve 44 located within the sleeve 31 in concentric relation thereto but whose lower end extends below the last noted sleeve. As indicated in Fig. 6, the links 29 and 42 are disposed on opposite sides of the vertical axis of the machine. The upper end of the sleeve 44 has secured thereto a flange 45 which seats within a suitable recess provided in the flange 32 (see Fig. 9). A plurality of circumferentially spaced apertures 46 is provided in the flange 45 40 to receive the projecting ends of drive pins 47 that are fixed in a cooperating flange 48 which seats in a corresponding recess in the flange 35. The flange 48 is secured to the lower end of a sleeve 49 that is located within the sleeve 36 45 in concentric relation thereto and which is in axial alignment with the short sleeve 44. The flanges 45 and 48, together with the driving pins 47, constitute a clutch for transmitting the drive to a group of inner agitators as presently described.

The upper end of the sleeve 49 is journaled in the sleeve 36 and beyond this point, the sleeve 49 is keyed to a hub sleeve 50 that surrounds and is partly journaled on the sleeve 38. A plurality of radially disposed and equispaced blades 51 and 52 are secured to the sleeve 50 and while these blades may possess any desired configuration and any dimensions, they are shown as short blades 51 and long blades 52 which are alternately disposed around the sleeve 50.

Stability of the foregoing concentric sleeve construction is maintained by a guidepost 53 which fits within the sleeve 49 and extends for substantially the full length thereof. The lower end of the post 53 seats within a pocket formed in a cap 54 that is secured to the strut 15 and endwise movement of the post is prevented by a setscrew 55 mounted in the cap 54 and having its end fitting within an annular groove 56 formed on the lower end of the post.

The foregoing completes the description of the various portions of the machine so far as its washing function is concerned and, in describ- 75

ing the operation of the machine during wash- 5 ing it will be understood that, due to the link connection between the yoke 28 and rock arm 38, the rotary movement of the crank arm 25 im- parts an oscillatory movement to the arm 38 and consequently to the basket 40. A similar oscillatory movement, but in an opposite direction, is imparted to the central or inner group of agitating blades by reason of the link connection between the yoke and rock arm 43.

During the washing operation, the blades 51 and 52 act to propel the cleaning liquid and the pieces being washed toward the wall of the basket, while the blades 41 exert a contrary action. Accordingly, the pieces are prevented from either collecting at the wall of the basket or from being impacted and balled together against the blade hub 50. In effect, the pieces are maintained in the cleaning liquid between the basket wall and the blade hub while undergoing periodic reversals of movement. At the same time, the pieces are subjected to the highly effective scrubbing action of the liquid created by the opposite, oscillatory movements of the blades 51 and 52, and 41. These movements not only direct the masses of the cleaning liquid along opposite sides of any piece of goods, but also directly through these pieces. The scrubbing action is further enhanced by the impact of masses of liquid moving in opposite directions. Insofar as it is possible to observe the movement of single pieces of material during the washing operation, it is believed that each piece traverses a path generally having the form of the figure 8. Since the pieces are not impacted against the basket wall or the sleeve hub 50, the washing action is free of any undue rubbing action by the metallic walls of the basket or tub that would result in wear on the pieces.

The dual link driving connection between the crank arm 25 and the concentric sleeves which are respectively connected to the inner and outer groups of agitating blades provides for a relative movement of the inner and outer blades that compensates for the greater radius of the outer group. In other words, if the angular movements of the two sets of blades were equal, then due to the greater radius of the outer group and the fact that the blade groups oscillate in equal times, the linear speed of the outer group would be greater than the inner group, and since this greater speed would be reflected in a greater thrust on the suds than that exerted by the inner blades, the suds agitated by the outer blades would tend to overcome the suds agitated by the central blades so that the pieces would tend to collect around the sleeve hub 50.

The crank arm 25 is characterized by a fixed throw and, since the connecting links 29 and 42 are of fixed length, then by suitably arranging the lengths of the rock arms 38 and 43 and properly relating the areas of the outer and inner groups of agitating blades, it is possible to obtain a substantial balance between the oppositely acting thrusts of these two blade groups to the end that the clothes are tumbled in the annular space between the blades. The foregoing arrangement can be easily effected by making the length of the rock arm 38 which actuates the basket and outer group of blades of a greater length than the rock arm 43. For example, in the relation of parts illustrated in the several figures, if the length of the rock arm 38 is 2½ inches and the length of the rock arm 43 is 2¼ inches, then the blades 41 will oscillate

through an arc of approximately 68 degrees, while the blades 51 and 52 will act through an arc of approximately 78 degrees in the same time. The agitating surface of each outer blade measures approximately $2\frac{3}{4}$ " x 7", while those of the large and small inner blades measure approximately 3" x $7\frac{1}{2}$ " and $1\frac{3}{4}$ " x 4", respectively. The diameter of the basket is about 23 $\frac{1}{2}$ inches. The foregoing dimensions and angular movements are intended by way of example only and not limitation.

After the washing operation has been completed, the basket 40 is elevated to the position illustrated in Fig. 2, i. e., above the surface of the cleaning liquid in the tub 13, and the basket is thereafter rapidly rotated to centrifugally extract the liquid from the wet pieces in the basket.

A reversible motor 57 is journaled in a bracket 58 that depends from the underside of an upper, channel strut 59 that extends transversely of the machine and has its ends fastened to the side walls of the container 10 just below the tub 13. A pulley 60 is mounted on one end of the motor shaft and operating around this pulley is a belt 61 which also operates around a driven pulley 62 that is fast upon the shaft of a worm 63 that is journaled in a housing 64 attached to the underside of the lower strut 15. The worm 63 meshes with a worm gear 65 that is pinned or otherwise secured to the lower end of a shaft 66 which extends upwardly through and is rotatably mounted in the lower strut 15. The upper end of the shaft 66 is journaled in a cap 67 provided on the upper strut 59, while the intermediate portion of the shaft 66 is formed as a screw 68. The screw portion of the shaft 66 extends for substantially the length thereof between the upper and lower struts and threaded thereon is a sleeve nut 69 from which extends laterally an arm 70 that encircles the outer sleeve 36 (see Fig. 9).

The arm 70 is concentrically counterbored with respect to the sleeve 36, as indicated by the numeral 71, and seated in the recess so formed is the lower race of a thrust bearing 72. A clutch ring 73 provided with any desired number of teeth is secured to the sleeve 36 and seats upon the upper race of the bearing 72. Accordingly, when the nut 69 is moved upwardly toward the position illustrated in Fig. 2, the thrust bearing 72 engages the clutch ring 73 and correspondingly shifts the sleeve 36 in the same direction, but when the nut 69 occupies the position illustrated in Fig. 9, the sleeve 36 can rotate freely during the washing operation.

A housing 74 is secured to the underside of the upper strut 59 in encircling relation to the sleeve 36 and a worm gear 75 having a hub 76 is journaled in the casing 74 in concentric relation to the sleeve 36. A bearing 77 is interposed between the hub 76 and the sleeve 36 and serves to provide an intermediate support for the concentric sleeve structure that counteracts sidewise thrust. The hub 76 projects downwardly through the bottom of the casing 74 and is provided with a plurality of circumferentially disposed teeth 78 which are intended to engage with the similar teeth provided on the clutch ring 73 when the basket has been raised to spinning position.

The worm gear 75 meshes with a worm 79 and the end thereof projects through the housing 74 and has secured thereon a pulley 80 which is driven by a belt 81 that operates around the outer groove provided on the pulley 18 (see Fig. 6). Therefore, as the motor 16 operates during the

washing operation, it also drives the worm gear mechanism encased within the housing 74, but this mechanism runs idly with respect to the sleeve 36 until the clutch ring 73 has been raised to the position illustrated in Fig. 2.

The motor 16 runs continuously during the washing and wringing operation, while the motor 57 operates only during the periods of raising and lowering the basket.

It will be understood that a suitable switch and electrical connections will be utilized with the motor 16 to insure its stopping and starting at the proper time and other connections and a reversing switch with the reversible motor 57 for raising and lowering the basket. These connections and switches, being well known in the art, and not forming any part of the present invention, have not been illustrated.

After the washing operation has been completed, the motor 57 is started rotating in the proper direction to initiate a movement of the nut 69 upwardly along the screw 68. This movement through the clutch ring 73 initiates an upward movement of the sleeve 36 and a withdrawal of the driving pins 34 from the apertures in the clutch flange 32. Further, the upward movement of the sleeve 36 causes a similar movement of the sleeve hub 50 and a withdrawal of the driving pins 47 from the apertures in the clutch flange 45. Therefore, shortly after the motor 57 begins rotating, the drive to the inner and outer groups of agitators is interrupted.

The motor 57 continues to operate until the clutch ring 73 engages the teeth 78, whereupon the motor 57 is stopped and the basket 40 is rotated rapidly by the motor 16 until the cleansing liquid is centrifugally extracted from the pieces in the basket and the pieces are in a damp dry condition. Thereafter, the pieces can be removed from the basket and the motor 57 reversed to return the basket to the lower or washing position.

By spin wringing the pieces in the same basket in which the same are washed, all manual handling of the pieces between the washing and wringing operations is eliminated. Moreover, and this feature constitutes a very important aspect of my invention, it is possible to wash and wring successive batches of clothing without wasting the suds in the tub 13. For example, successive batches of white, colored and more severely soiled pieces can be washed and damp wrung in succession in the machine and the same suds employed to wash each batch.

I claim:

In a washing machine, the combination of a basket for receiving the pieces to be washed, means for imparting an oscillatory movement to the basket around the axis thereof, radial blades of substantial width carried by the peripheral wall of the basket for directing cleansing liquids and pieces inwardly of the basket when oscillated, a centrally disposed agitator in the basket having radial blades of substantial width and of a larger area than the basket blades for directing liquid and pieces toward the basket wall, and means for imparting a rotary oscillating movement to the agitator opposite to and of greater amplitude than the basket, the blades being so constructed and arranged relative to their respective amplitudes that the pieces are substantially maintained in the annular space between the blades during the washing operation.
